UNITED STATES PATENT OFFICE.

PHILETUS WARREN GATES, OF CHICAGO, ILLINOIS.

DESIGN FOR A FRAME FOR ROCK AND ORE CRUSHERS.

SPECIFICATION forming part of Design No. 29,155, dated August 2, 1898.

Application filed April 30, 1897. Serial No. 634,646. Term of patent 14 years.

To all whom it may concern:

Be it known that I, PHILETUS WARREN GATES, a citizen of the United States, residing at Chicago, in the county of Cook and 5 State of Illinois, have invented and produced a new and original Design in Frames for Rock and Ore Crushers, reference being had to the accompanying drawing, forming a part hereof.

In the accompanying drawing, which forms 10 a part of this specification, the figure represents a perspective view of my design.

The leading feature of my design consists, substantially, in a base portion provided with 15 a plurality of pillars supporting an upper substantially circular portion.

A is the base portion, B B B B the upright pillar portions, and C the upper substantially circular portion, the whole presenting to the eye a harmonious and ornate figure, as shown in the accompanying drawing. 20

I claim—

The design for a frame for rock and ore crushers, substantially as herein shown and described.

PHILETUS WARREN GATES.
